MOTOR FUEL PRODUCTION

George Armistead, Jr., Scarsdale, N. Y., assignor
to Gasoline Products Company, Inc., Newark,
N. J., a corporation of Delaware

Application October 23, 1937, Serial No. 170,602

2 Claims. (Cl. 196—49)

This invention relates to the treatment of hydrocarbon oil to produce lighter hydrocarbons therefrom. More particularly, the invention relates to the treatment of crude oil or partially topped crude oil to effect conversion thereof to motor fuel and other valuable products under conditions of highest efficiency with the production of gasoline constituents of high anti-knock value.

10 It is an object of the invention to produce a method of treating a plurality of hydrocarbon oils of varying boiling ranges, and intermediate products produced from said hydrocarbon oils, separately under conditions selected for each material, to produce therefrom motor-fuel products, and intermediate products suitable for further conversion, under conditions selected for each treatment to effect a combined operation of highest efficiency whereby motor fuel of high 15 anti-knock value is produced with minimum production of gas and undesirable heavy products and deposition of coke.

It is a further object of the invention to provide a method whereby crude oil or partially 25 topped crude oil may be efficiently treated under the above-described conditions by separating said oil into various fractions and treating said fractions and intermediate products produced therefrom under said separate conditions for maximum over-all efficiency.

30 It is a further object of the invention to provide a process of the above nature wherein heavy naphtha and a relatively heavy hydrocarbon oil such as reduced crude are simultaneously treated in combination to effect reforming of the naphtha to produce gasoline constituents of improved anti-knock value with simultaneous minimum production of gas and the cracking of the reduced crude to produce gasoline constituents of high 35 anti-knock value.

It is a further object of the invention to produce a method of the above nature wherein a condensate produced in the system and of relatively great refractoriness is treated in combination in the system to effect maximum conversion thereof to gasoline constituents of high anti-knock value under conditions of highest efficiency.

50 It is a further object of the invention to produce a method of the above nature whereby hydrocarbon oils of varying boiling ranges, and intermediate fractions produced therefrom, are treated under conditions of maximum efficiency 55 to produce motor-fuel constituents of high anti-

knock value with a minimum requirement of apparatus.

The invention contemplates the treatment substantially in combination of a plurality of fractions of hydrocarbon oil of different boiling ranges whereby a light fraction, which may be heavy naphtha, and an intermediate fraction, which may be a virgin gas oil, are separately subjected to elevated conditions of temperature and pressure to effect reforming of the heavy naphtha to produce constituents of improved anti-knock value, and substantial cracking and conversion of the intermediate fraction to products in the gasoline boiling range. A heavy fraction such as heavy gas oil or reduced crude is combined with the naphtha fraction after said reforming treatment, and the thus merged products are subjected to cracking conditions of temperature and pressure to effect cracking of the heavy fraction and conversion thereof to lighter products with additional reforming of the heavy naphtha to the desired extent. The combined treatment of the heavy naphtha and heavy hydrocarbon oil fraction may be suitably carried out in a single elongated heating zone of restricted cross section, such as a pipe coil, whereby the heavier oil is introduced into the coil at an intermediate point or points selected whereby the heavy naphtha is first subjected to the desired reforming conditions of temperature and pressure whereby substantial 30 reforming is effected prior to the admixture therewith of the said heavy hydrocarbon oil. The merged products are thereafter passed through the remainder of the coil under conditions selected to produce the desired cracking of the 35 heavy oil with or without further reforming treatment of the heavy naphtha.

The said intermediate fraction which may be a virgin gas oil is simultaneously separately subjected to elevated conditions of temperature and pressure, for example, in a separate elongated heating zone of restricted cross section to effect substantial cracking and conversion thereof on a once-through basis to produce therefrom a maximum proportion of gasoline constituents of high 40 anti-knock value.

The products of the last-mentioned cracking treatment and the products from the combined treatment of heavy hydrocarbon oil and heavy naphtha are separated in admixture or separately 50 into vapors and liquid residue and the resulting vapors are fractionated jointly or separately to separate therefrom condensate and desired distillate. The vapors from either or both cracking operations may be fractionated to separate there- 55

from a heavy naphtha fraction, which may be combined with the first-mentioned heavy naphtha for reforming treatment therewith, or which may be separately treated.

Condensate separated from the vapors produced from one or both of the aforementioned cracking treatments is separately subjected to elevated conditions of temperature and pressure, for example, in a third elongated zone of restricted cross section to effect cracking and conversion thereof to lighter products including gasoline constituents. The cracked products from the last-mentioned cracking treatment are separated into vapors and liquid residue, and the vapors are fractionated to form therefrom a condensate and a desired distillate. The above-mentioned separation of cracked products may be carried out alone or jointly with the separation of other cracked products in the system. Similarly, the above-mentioned fractionation may be carried out alone or in combination with the fractionation of other vapors produced in the system. Preferably, however, the separation and fractionation of the cracked products from the last-mentioned cracking treatment are carried out separately whereby a separate condensate is obtained therefrom. This condensate may be returned to the system for further cracking treatment by combining it with the heavy naphtha prior to the passage thereof to the first-mentioned heating zone whereby said condensate is subjected to cracking conditions of temperature and pressure during the said reforming treatment to effect conversion thereof to lighter products including gasoline constituents; or the last-mentioned condensate may be combined with the products of cracking from the second-mentioned cracking operation. Conveniently this may be accomplished by using said condensate as a cooling liquid for admixture with the hot products from said cracking operation whereby the said condensate is combined with said cracked products and recovered as condensate together with the material of similar boiling point contained in the cracked products; or the condensate may be admixed with the said cracked products by introduction as reflux in the fractionation of the vapors from said cracking treatment; or the said condensate may be admixed with cracked products from any cracking operation in the system from which a similar condensate is collected for passage to the third-mentioned elongated heating zone.

Specifically, the invention contemplates the distillation of crude oil or partially topped crude oil to separate therefrom a light fraction which may be a heavy naphtha, a heavy fraction which may be a reduced crude or a heavy gas oil, and an intermediate fraction having a boiling range intermediate that of the said heavy and light fractions, and the treatment, in combination, of the fractions thus obtained in the manner described above.

The naphtha distillates produced in each cracking treatment may be recovered separately or in combination, and the gasolines thus obtained may be subjected to any further desired treatment. Separately collected gasoline fractions may be separately treated or may be blended in any desired proportions for further treatment.

The invention will be further described by reference to specific embodiments. It is to be understood, however, that the invention is not limited by such specific reference but is capable of other embodiments within the spirit and scope of the invention.

The accompanying drawing is a flow diagram of an apparatus suitable for carrying out the present invention. The invention will be specifically described by reference to specific embodiments carried out in the apparatus illustrated and by reference to the drawing. It is to be understood, however, that the invention is limited in no way by the drawing but is capable of other embodiments than those described and which may be beyond the physical limitations of the apparatus indicated.

Referring to the drawing, crude oil or partially topped crude oil is introduced to the system through line 1 provided with a pump 2. The crude oil so introduced is heated to a distillation temperature to effect subsequent separation by distillation into vapors and a liquid residue whereby fractions separated from the vapors and the said residue are suitable for further treatment in the system. The preliminary heating of the crude oil may be accomplished by suitable heat exchange with hot products produced within the system or other similar means. In addition to such treatment the crude oil may be heated by passage through an elongated heating zone of restricted cross section such as a coil located in a heater; or the preliminary heating of the crude oil may be accomplished entirely by the last-mentioned means. For purposes of simplicity in illustration the heating of the crude oil is represented in the drawing as being accomplished entirely by passage through a separate heater 3 provided with a suitable coil.

Heater 3 and heaters 4, 5 and 6, whose functions will be described below, are shown as separate entities for purposes of illustration. It is to be understood, however, that the functions of these heaters may be performed by several coils each located in a furnace structure which also houses one or more other coils, the coils being arranged in various parts of the furnace in accordance with the temperatures desired to be imparted to the materials passing through the coils. For example, all of the said coils may be housed in a single furnace structure.

In heater 3 the crude oil is heated to a temperature sufficient to effect subsequent vaporization to the desired degree. For example, the crude oil may be heated in heater 3 to a temperature of 500° to 800° F. at a pressure varying from atmospheric up to 100 pounds per square inch.

The heated crude oil is withdrawn from heater 3 through line 7 and introduced into the lower portion of crude flash tower 8 with or without reduction in pressure by means of valve 9 located in line 7. In tower 8 conditions of temperature and pressure are maintained to effect vaporization of constituents boiling at 650° to 750° F. and lower. The resulting reduced crude collects in the bottom of tower 8, and additional heat may be applied at that point to assist in the desired vaporization, for example, by means of a heating coil 10.

The vapors ascend tower 8 and are fractionated in the upper portion thereof to effect the separation of heavy constituents therefrom and permit the passage overhead of a vapor consisting of light naphtha constituents and lighter products. Suitable cooling means such as a cooling coil 11 may be provided in the upper portion of tower 8 to effect the desired fractionation. Trap-out trays 12 and 13 are provided at intermediate points in the tower 8 to collect a heavy naphtha condensate and a gas-oil condensate, respectively. Either or both of these condensate

cuts may contain the kerosene fractions usually found between the gasoline and gas oil fractions and the gas oil cut may, under some circumstances, be of substantially a kerosene character.

5 The above-described separation of the crude oil into reduced crude and gas oil and heavy naphtha condensates is for purposes of illustration only. The reduced crude so separated may be used as such in the process of the invention, or
10 the crude oil may be further distilled to separate therefrom vapors from which a heavy gas-oil condensate may be separated, for example, one having an initial boiling point of 650° to 750° F. This may be accomplished in a single vaporization step or in a plurality of stages. For example, the reduced crude collected in the bottom of tower 8 may be further distilled by separate means (not shown), such as, for example, by vacuum, to effect the production of a heavy gas-oil
15 condensate which may be used in the modifications of the process of the invention described below in place of the reduced crude referred to therein.

To effect the specific separation illustrated, 25 however, tower 8 may be operated at a pressure of atmospheric to 100 pounds per square inch with a bottom temperature of 500° to 750° F. and a top temperature of 250° to 350° F. to effect the passage overhead of a light naphtha distillate 30 and the collection in the bottom of a reduced crude having a gravity of, for example, 20° to 26° A. P. I.

Line 14 connects the trap-out tray 12 and the inlet of the coil of the heater 4. Pump 15 is 35 provided in line 14 to effect transfer of heavy naphtha from the trap-out tray 12 to the inlet of the coil of heater 4. Line 16 connects the bottom of tower 8 with an intermediate point or points of the coil of heater 4 and is provided with 40 a pump 17 to effect the introduction of reduced crude from the bottom of tower 8 into the coil of heater 4 at at least one intermediate point therein. The connection between line 16 and the coil of heater 4 is arranged whereby a substantial portion of the coil lies between the connection and the inlet of the coil whereby the heavy naphtha introduced through line 14 passes 45 through a substantial portion of the coil and may be subjected to the desired elevated conditions of temperature and pressure to effect substantial reforming thereof prior to the admixture therewith of reduced crude introduced through line 16. In that portion of the coil of heater 4 located between the connection with line 14 and the connection with line 16 the hydrocarbon oil passing therethrough is heated to a temperature of 500° to 1100° F. at a pressure of 200 to 1000 pounds per square inch. For example, it may be heated to a temperature of 1025° F. at 500 50 pounds per square inch.

The reduced crude may be preheated by suitable means not shown prior to introduction into the coil of heater 4, and its temperature, the proportion thereof introduced and the rate of 55 application of heat to that portion of the coil lying between the connection with line 16 and the exit thereof are regulated to effect the desired treatment of the merged products therein. For example, the merged products may be maintained under conditions necessary to effect substantial cracking of the heavier constituents with additional reforming of the naphtha constituents, and that portion of the coil may be maintained at a pressure the same or lower than that 60 obtaining in the portion of the coil lying between 75

the entrance and the connection with line 16, with a final exit temperature of 800° to 975° F., for example, 900° F. Conveniently, the coil of heater 4 may be arranged within the furnace housing whereby that portion of the coil through 5 which the merged products pass lies in a cooler portion of the furnace and functions as a soaking section for the reforming treatment as well as for the cracking of the reduced crude in the combined section. 10

The outlet of the coil of heater 4 is connected by line 18 with the lower portion of evaporator 19 whereby the cracked products from heater 4 may be introduced into evaporator 19 with or without any desired reduction in pressure by 15 means of valve 20 located in line 18. Conditions of temperature and pressure in evaporator 19 are controlled to effect vaporization and passage overhead of constituents suitable for further cracking treatment and lighter products. 20 Suitable baffling means may be provided to assist in the removal of entrained material from said vapors and for fractionation effected by the introduction of reflux through line 21. The upper portion of evaporator 19 is connected with the 25 lower portion of a fractionator 22 by means of line 23 provided with a valve 24.

Fractionator 22 is provided with cooling means in the upper portion thereof, for example, a cooling coil 25, to effect the fractionation of the vapors to permit the separation therefrom of a gas oil condensate, optionally, the separation of a heavy naphtha condensate, and the passage overhead of a light naphtha distillate and lighter products. For example, fractionator 22 may be 30 maintained at a pressure of 25 to 200 pounds per square inch with a top temperature of 250° to 350° F. A trap-out tray 26 may be provided at an intermediate point in the fractionator 22 to effect the collection of a heavy naphtha condensate. 35

Line 28 connects the trap-out tray 13 and the inlet of the coil of heater 5 and is provided with a pump 29 to effect the passage of virgin gas oil collected in trap-out tray 13 through the coil of 40 heater 5.

In heater 5 the virgin gas oil is subjected to suitable cracking conditions of temperature and pressure to effect a relatively high rate of conversion to gasoline constituents. When cracking 45 to the extent that the conversion products contain 25% or more of 420° end point gasoline the virgin gas oil may be heated at a pressure of 500 to 2000 pounds per square inch or more with a final temperature of 850° to 1050° F. For example, the virgin gas oil may be heated under a pressure of 500 pounds per square inch to an exit temperature of 950° F. with the contact time regulated to effect the desired degree of conversion. 50

The products of the cracking of the virgin gas oil in heater 5 may be discharged therefrom through line 30 which connects with the lower portion of an evaporator 31 whereby the cracked products are introduced into the evaporator 31 60 for separation thereof into vapors and liquid residue. One or more valves 32 and 33 may be provided in line 30 to effect any desired reduction in pressure on the cracked products. Conditions of temperature and pressure in the evaporator 31 65 are maintained to effect vaporization and passage overhead of constituents suitable for further cracking treatment and lighter products. Suitable baffle means may be provided for the removal of entrained material from the vapors in the up- 70 75

per portion of evaporator 31 and for fractionation effected by means of reflux introduced at the top of evaporator 31 through line 34.

The upper portion of evaporator 31 is connected with the lower portion of a fractionator 35 by means of line 36 through which the vapors passing overhead from evaporator 31 are introduced into the fractionator 35. Fractionator 35 is provided with cooling means in the upper portion thereof, for example, a cooling coil 38 to effect fractionation of the vapors and permit the separation therefrom of a gas-oil condensate and, optionally, the separation of the heavy naphtha condensate and the passage overhead of a light naphtha distillate and lighter products. For example, fractionator 35 may be maintained at a pressure of 25 to 250 pounds per square inch with a top temperature of 250° to 350° F. A trap-out tray 39 may be provided at an intermediate point 20 in the fractionator 35 to effect the collection of a heavy naphtha condensate.

Line 41 connects transfer lines 18 and 30 whereby the cracked products from heaters 4 and 5 may be combined for common treatment in evaporator 31. Valve 42 is provided in line 41 whereby the distribution of cracked products from heater 4 between evaporator 19 and evaporator 31 may be controlled by manipulation of valves 20 and 42.

Line 43 connects lines 23 and 36 whereby the vapors passing overhead from evaporator 19 may be combined with vapors passing overhead from evaporator 31 and the combined vapors introduced into fractionator 35 for common treatment therein. A valve 44 is provided in line 43, and this valve, together with valve 24, permits the desired distribution of vapors from an evaporator 19 between fractionators 22 and 35.

Line 45 connects the lower portion of fractionator 35 with the inlet of the coil of heater 6 whereby condensate collected in the lower portion of fractionator 35 may be treated in heater 6. Pump 46 is provided in line 45 to effect the passage of the condensate through the coil of heater 6. Line 47 connects the lower portion of fractionator 22 with line 45 whereby all or a portion of the condensate collected in the bottom of fractionator 22 may be combined with the condensate from fractionator 35 for common treatment in heater 6.

In heater 6 the condensate is subjected to cracking conditions of temperature and pressure to effect substantial conversion to lighter products including gasoline constituents. Preferably, however, the condensate in heater 6 is subjected to a lesser degree of conversion than the gas oil in heater 5 because of the nature of the condensate constituting the fresh feed to heater 6. The condensate in heater 6 may be heated at a pressure of 50 to 400 pounds and at a temperature of 875° to 1100° F. For example, the condensate may be heated under a pressure of 200 pounds per square inch to a final temperature of 900° to 950° F. to effect a 10% to 25% conversion to gasoline constituents.

The products of the cracking treatment in heater 6 are discharged therefrom through line 48 which connects the outlet of the coil of heater 6 with the lower portion of an evaporator 49 whereby the cracked products from heater 6 may be introduced into evaporator 49 to effect separation thereof into vapors and liquid residue. Line 50 connects line 48 with the lower portion of evaporator 31 whereby all or a portion of the cracked products from heater 6 may be introduced into evaporator 31 for separation therein. Valves

51 and 52 are provided in lines 48 and 50, respectively, to permit the desired reduction in pressure on the cracked products and to permit any desired distribution of said cracked products to evaporators 31 and 49.

The evaporator 49 is controlled to effect vaporization and passage overhead of constituents suitable or desired for further cracking treatment and lighter products. Suitable baffling means may be provided in the upper portion of evaporator 49 to assist in the removal of entrained material from the vapors and to permit fractionation by means of reflux introduced at the top of the vessel through line 98.

The upper portion of evaporator 49 is connected with the lower portion of a fractionator 53 by means of line 54 provided with a valve 55 whereby vapors passing overhead from evaporator 49 are introduced into fractionator 53. Line 56 connects line 54 with the lower portion of the fractionator 35 whereby vapors passing overhead from evaporator 49 may be partially or entirely introduced into fractionator 35 for fractionation treatment therein in the manner described. A valve 57 is provided in line 56, and by means of this valve and valve 55 any desired distribution of the vapors to fractionators 35 and 53 may be effected. Fractionator 53 is operated to effect the fractionation of the vapors and separation therefrom of a desired condensate and the passage overhead of a desired distillate and may be maintained at a pressure of 25 to 250 pounds per square inch with a top temperature of 350° to 450° to effect the desired fractionation. A cooling coil 58 or other suitable cooling means may be located in the upper portion of fractionator 53 to effect the desired temperature control.

Line 60 connects the lower portion of fractionator 53 with line 14 and is provided with a pump 61 whereby condensate collected in the bottom of fractionator 53 may be combined with the heavy naphtha passing through line 14 to the reforming treatment in heater 4. Line 62 connects line 60 and transfer line 30, preferably after at least one reduction in pressure whereby all or a portion of the condensate in line 60 may be diverted therefrom for admixture with the hot products of conversion from heater 5 to cool said hot products and arrest cracking. Valves 63 and 64 are provided in lines 60 and 62, respectively, to permit any desired distribution of condensate between heater 4 and transfer line 30.

Line 65 connects line 60 with the upper portion of fractionator 35 whereby all or a portion of the condensate from fractionator 53 may be introduced into fractionator 35 as reflux medium. Valves 66 and 67 are provided in lines 60 and 65, respectively, to permit any desired distribution of condensate between line 60 and line 65.

As an alternative method of handling the gas oil condensate in the base of tower 53, it might pass through line 100 to heat exchanger 101 where it passes in indirect heat exchange with incoming cold crude and serves to preheat the latter before its entrance to heater 3. Line 102 conducts the gas oil condensate from heat exchanger 101 to a tank 103 where it may mix with stocks of a similar character from sources not shown. From tank 103 the gas oil may pass through line 104 and pump 105 to a heat exchanger 106 located on the transfer line 48 from heater 6; or all or a part thereof may be diverted through line 109 to line 62 for admixture in transfer line 30 as described; or all or a part thereof may be diverted through line 111 to line 75

65 for introduction into fractionator 35 as described. Valves 110, 112 and 113 are provided in lines 103, 111 and 104, respectively, to effect the desired distribution. After acquiring heat in ex- 5 changer 106 the gas oil passes through line 107 back into line 60 through which it may be passed to the entrance of heater 4 as previously described.

The liquid residue from evaporators 19, 31 and 10 49 may be withdrawn therefrom through lines 68, 69 and 70, respectively, for treatment elsewhere for the recovery of valuable constituents therefrom or for use as fuel.

The uncondensed gases passing overhead from 15 flash tower 8 and fractionators 22, 35 and 53 are withdrawn therefrom through lines 71, 72, 73 and 74, respectively, and passed through coolers 75, 76, 77 and 78 to effect liquefaction of gasoline constituents therein. The condensate thus obtained 20 is introduced into collectors 79, 80, 81 and 82, respectively, for separation of uncondensed gases. The gases may be withdrawn from the said collectors and from the system through lines 83, 84, 85 and 86. The resulting gasoline condensates 25 may be separately withdrawn from the collectors through lines 87, 88, 89 and 90, respectively; or all or a portion of any or all of the gasoline condensates may be withdrawn from the collectors through lines 91, 92, 93 and 94 which connect 30 with a common line 95 whereby any gasoline fractions withdrawn through lines 91, 92, 93 and 94 may be blended as desired.

Line 96 connects trap-out tray 39 with line 14, and line 97 connects trap-out tray 26 with line 96 whereby heavy naphtha collecting in these trap-out trays may be passed wholly or in part to admixture with the heavy naphtha from trap-out tray 12 and subsequent reforming treatment in heater 4.

40 It is to be understood that the various hot products produced in the system may be cooled intermediate or prior to further treatment by suitable cooling means not shown. For example, suitable cooling means may be provided to effect reduction 45 in temperature of the cracked products in lines 18, 41, 30, 50 or 48.

Fractionating towers 8, 22, 35 and 53 may be provided with suitable gas and liquid contact 50 means to facilitate the absorption, evaporation, condensation, and stripping incidental to fractionation.

The heaters 4, 5 and 6 are shown as comprising 55 essentially a coil located in a heating chamber to effect cracking treatment of the hydrocarbons passing therethrough. The complete treatment desired may be carried out in the coils or, in addition, one or more insulated reaction zones of enlarged diameter may be provided to assist in the desired treatment in connection with one 60 or more of heaters 4, 5 and 6.

Separate draw-off means may be provided for withdrawing intermediate products from the system as required by variations in the process. Such means are not shown in the drawing for 65 simplicity of illustration. It is obvious, however, that the invention is not limited, for example, to the treatment of all the virgin gas oil from trap-out tray 13 or the return to the system for further treatment of all the condensate from fractionator 70 53. Any desired proportion of these and other intermediate products may be employed for further treatment, as required by the operation of the process, and it is to be understood that the invention is not limited by the mere absence of 75 means for such separate draw-off in the drawing.

According to a preferred modification of the invention heavy naphtha from trap-out tray 12 is introduced into the coil of heater 4 together with relatively refractory cycle gas oil from line 60, and the combined stream is subjected to elevated conditions of temperature and pressure to effect reforming of the heavy naphtha and cracking of the cycle gas oil to lighter products including gasoline constituents. For example, the combined stream may be heated to a temperature 10 of 1000° F. at a pressure of 500 pounds per square inch for a time sufficient to effect 15 to 20% conversion of the cycle gas oil to gasoline constituents.

Reduced crude from the bottom of tower 8 is 15 passed through line 16 and introduced into the coil of heater 4 at a point or points substantially removed from the inlet of the coil whereby the above-mentioned combined stream is subjected to cracking conditions for a time sufficient 20 to effect substantial conversion prior to the admixture therewith of the reduced crude from line 16. The merged products are thereafter passed through the remainder of the coil of heater 4 under temperature and pressure conditions sufficient to effect conversion of the reduced crude to lighter products including gasoline constituents of high anti-knock value and a substantial proportion of products above the gasoline boiling range. For example, the merged 25 stream may be heated to a temperature of 875° to 900° F. while being maintained at the same pressure.

The cracked products from heater 4 pass 30 through line 18 to evaporator 19, the pressure 35 being reduced to that of the evaporator by means of valve 20. Evaporator 19 is maintained at pressure and temperature conditions suitable to effect vaporization overhead of constituents suitable for further cracking treatment and the separation 40 of a residue suitable for fuel. For example, the evaporator 19 may be maintained at a pressure of 75 pounds per square inch with a bottom temperature of 750° to 800° F. and a top temperature of 650° to 750° F. The liquid residue 45 is withdrawn through line 68, and the vapors pass overhead through line 23 for introduction into fractionator 22. In fractionator 22 conditions of temperature and pressure are maintained to effect condensation of a suitable cycle 50 stock which collects in the bottom of fractionator 22, the recovery of a heavy naphtha condensate and the collection thereof in trap-out tray 26 and the passage overhead of vapors containing light naphtha and lighter constituents. 55 For example, fractionator 22 may be maintained with a bottom temperature of 525° to 600° F. and a top temperature of 300° F. at a pressure of 75 pounds per square inch.

Virgin gas oil collected in trap-out tray 13 is 60 introduced into the inlet of the coil of heater 5 through line 28 and is subjected in heater 5 to temperature and pressure conditions sufficient to effect substantial conversion to lighter products. For example, the virgin gas oil may be 65 subjected to a temperature of 900° to 950° F. at a pressure of 400 pounds per square inch for a time sufficient to effect 25 to 30% conversion to gasoline constituents.

The cracked products from heater 4 are with- 70 drawn through line 30 for introduction into evaporator 31 wherein temperature and pressure conditions are maintained to effect vaporization of constituents suitable for further crack- 75 ing into lighter products and the separation of 75

a liquid residue suitable as fuel. For example, evaporator 30 may be maintained at a pressure of 75 pounds per square inch, the reduction in pressure from heater 5 being effected by means of valve 32 and/or valve 33. To assist in the desired vaporization a temperature of 750° to 800° F. may be maintained in the base of evaporator 31, and the top held at 650° to 750° by means of reflux.

10 The liquid residue from evaporator 31 is withdrawn through line 69, and the vapors pass overhead through line 36 for introduction into fractionator 35.

15 In fractionator 35 conditions of temperature and pressure are maintained to effect the passage overhead of vapors including light naphtha and lighter products, the collection in the bottom of fractionator 35 of a condensate suitable for further cracking treatment and the recovery 20 of a heavy naphtha condensate and its collection in trap-out tray 39. For example, fractionator 35 may be maintained at a bottom temperature of 525° to 600° F. and a top temperature of 300° F. at a pressure of 75 pounds per square inch.

25 The heavy naphtha collected in trap-out trays 26 and 39 is withdrawn therefrom through lines 96 and 97 and combined with the heavy naphtha from trap-out tray 12 for passage to the above-described reforming treatment.

30 The cycle condensate collected in the bottom of fractionator 35 is withdrawn therefrom through line 45 for introduction to the inlet of the coil of heater 6. The cycle condensate collected in the bottom of fractionator 22 is withdrawn therefrom through line 47 and combined with the condensate passing through line 45 to heater 6. In heater 6 the condensate passing through the coil thereof is heated under temperature and pressure conditions sufficient to effect 35 conversion thereof to lower-boiling products including gasoline constituents. For example, the materials passing therethrough may be heated to a temperature of 1000° F. at a pressure of 400 pounds per square inch for a time sufficient to effect 15 to 20% conversion to gasoline constituents.

35 Cracked products from heater 6 are withdrawn therefrom through line 48 and introduced into evaporator 49 wherein conditions of temperature and pressure are maintained to effect vaporization of constituents suitable for further cracking treatment and lighter products and the separation of a liquid residue suitable for use as fuel. For example, evaporator 49 may be maintained at a pressure of 75 pounds per square inch, the reduction in pressure from heater 6 being effected by means of valve 51 and with a bottom temperature of 750° to 800° F.

40 The liquid residue separated in evaporator 49 is withdrawn therefrom through line 7, and the vapors passing overhead are withdrawn through line 54 for introduction into fractionator 53 which is maintained under pressure and temperature conditions suitable to effect the condensation of constituents above the gasoline boiling range and the passage overhead of vapors including gasoline constituents and lighter products. For example, fractionator 53 may be maintained with a bottom temperature of 90° F. and a top temperature of 550° to 625° F. at a pressure of 75 pounds per square inch.

45 The condensate collected in the bottom of fractionator 53 is withdrawn therefrom through line 60 for admixture with the heavy naphtha in line 14 and passage therewith through the

coil of heater 4. The condensate may be passed directly to heater 4 or preliminarily may be passed through heat exchangers 101 and 106 as described.

5 The vapors passing overhead through lines 71, 72 and 73 are treated as described above to effect the separation and collection of the gasoline constituents therein which may be separately collected or blended in the manner described above.

10 According to another preferred modification of the invention the heavy naphtha passing through line 14 is passed through the first part of the coil of heater 4 and subjected to reforming conditions of temperature and pressure without the admixture therewith of condensate from line 60. Reduced crude is introduced through line 16 for cracking treatment as described above, and the cracked products are passed through lines 18, 41 and 30 for introduction into evaporator 31 for treatment therein in the manner described in connection with this evaporator. Virgin gas oil is subjected to conversion conditions in heater 5 in the manner described, and cycle condensate from line 60 is diverted through line 62 for admixture with the conversion products from heater 5 in line 30 with or without reduction in pressure by means of valve 33 to effect cooling of the cracked products and to arrest cracking. The combined products are then introduced through line 30 into evaporator 31 for treatment therein with further reduction in pressure, if necessary, by means of valve 32. If desired all or a portion of the condensate from fractionator 53 may be introduced as reflux into fractionator 35 through line 65. If desired, in operating in accordance with this modification the use of evaporator 49 and fractionator 53 may be omitted, the cracked products from heater 6 being passed through lines 48 and 50 for introduction into evaporator 31 for treatment therein; or only fractionator 53 may be omitted, the evaporator 49 being utilized to effect collection of a separate fuel through lines 70 and the vapors being introduced into fractionator 35 through line 56.

15 In either of the preferred modifications the use of evaporator 19 and fractionator 22 may be avoided by the introduction of the cracked products from heater 4 into evaporator 31; or only fractionator 22 may be omitted in which case the vapors from evaporator 19 are combined with those from evaporator 31 by passage through line 43. The use of separate evaporators 19 and 31, however, is useful in developing separate fuels of desired differing characteristics.

20 The present invention, as exemplified in the first-described preferred modification, permits the treatment of a plurality of oils of differing boiling ranges such as the various fractions resulting from distillation of crude oil to effect maximum production of gasoline products of high anti-knock value under conditions of maximum efficiency. The cracking of the reduced crude by admixture with the totally or partially reformed heavy naphtha permits a more drastic treatment of the reduced crude than is feasible in the treatment of this material alone and the production therefrom of gasoline constituents of high anti-knock value at the same time that substantial quantities of heavier products suitable for further conversion are obtained. The separate cracking of the virgin gas oil permits the relatively drastic treatment of this material to effect substantial conversion and production

of a high percentage of gasoline constituents of high anti-knock value. The cycle stocks from the reforming treatment and the cracking of the virgin gas oil and gas oil constituents from the cracking of the reduced crude are efficiently treated in heater 6 wherein they are subjected to the conditions of temperature and pressure most suitable to effect substantial conversion to gasoline constituents of high anti-knock value. 5

10 under conditions of maximum efficiency for such material. The condensate collected in the bottom of fractionator 53 ordinarily will comprise materials which have resisted cracking in passage through heaters 4, 5 and 6 and will therefore be relatively refractory in character. This material is advantageously treated by combining it with the heavy naphtha to be reformed in heater 4 wherein it will be subjected to drastic conditions of temperature and pressure necessary to effect cracking and production of gasoline constituents of high anti-knock value. 15

15 20

25 According to the second preferred modification condensate recovered in fractionator 53 is returned to the system for further treatment, and constituents suitable for further conversion treatment recovered in fractionator 35 are passed for cracking treatment in heater 6 wherefore complete conversion of the charge to the system to final products is accomplished.

30 These and other advantages are apparent from the foregoing description which has been made with reference to specific embodiments of the invention. It is to be understood, however, that the invention is not limited by such specific reference but that the advantages claimed for this invention reside in other modifications and embodiments which may be beyond the physical limitations of the apparatus described. 35

I claim:

40 1. The method of treating hydrocarbon oil that comprises distilling crude petroleum to produce therefrom a low boiling fraction comprising gasoline constituents, a high boiling fraction and an intermediate fraction higher boiling than gasoline, passing said low boiling fraction through an elongated cracking zone under superatmospheric pressure while applying heat thereto to subject said fraction to reforming temperature and effect conversion of gasoline constituents into constituents of increased anti-knock value, introducing said high boiling fraction into said elongated cracking zone intermediate the ends thereof and into intimate mixture with the stream of products undergoing reforming therein to thereby raise the high boiling fraction to a desired cracking temperature and subject it to cracking during the passage of the resultant mixture through the remainder of the elongated cracking zone, separating the resultant cracked

45 50

55 products from the elongated cracking zone into vapors and residue and fractionating the vapors to separate a desired gasoline product from higher boiling reflux condensate, directing said intermediate fraction to a second cracking zone and subjecting it therein to cracking conditions of temperature and pressure to effect conversion into gasoline constituents, separating the resultant cracked products into vapors and residue, fractionating the separated vapors to form a distillate comprising gasoline and a reflux condensate, combining the latter reflux condensate with aforesaid higher boiling reflux condensate and advancing the mixture to a third cracking zone wherein it is subjected to cracking conditions of temperature and pressure to effect conversion into gasoline constituents, separating the resultant cracked products from the third cracking zone into vapors and residue and fractionating the separated vapors to recover a desired gasoline product. 10 15 20 25 30 35 40 45 50 55

2. The method of treating hydrocarbon oils that comprises distilling crude petroleum to separate vapors from residue and fractionating the vapors to form a low boiling fraction comprising gasoline constituents and a higher boiling fraction, passing said low boiling fraction through an elongated cracking zone under superatmospheric pressure while applying heat thereto to subject said fraction to reforming temperature and effect conversion of gasoline constituents into constituents of increased anti-knock value, introducing said residue into said elongated cracking zone intermediate the ends thereof and into intimate mixture with the stream of products undergoing reforming therein to thereby raise the residue to a desired cracking temperature and subject it to cracking during the passage of the resultant mixture through the remainder of the elongated cracking zone, separating the resultant cracked products from the elongated cracking zone into vapors and residue, directing said higher boiling fraction to a second cracking zone and subjecting it therein to cracking conditions of temperature and pressure to effect conversion into gasoline constituents, separating the resultant cracked products into vapors and residue, fractionating said separated vapors recovered from said cracking operations to form a distillate comprising gasoline and a reflux condensate, advancing said reflux condensate to a third cracking zone and subjecting it therein to cracking conditions of temperature and pressure to effect conversion into gasoline constituents, separating the resultant cracked products from the third cracking zone into vapors and residue, and fractionating the separated vapors to form a distillate comprising gasoline. 30 35 40 45 50 55
